W. H. HILL

KEROSENE VAPORIZER

Filed July 3, 1918

UNITED STATES PATENT OFFICE.

WILLIAM H. HILL, OF MANATI, PORTO RICO.

KEROSENE VAPORIZER.

Application filed July 3, 1918. Serial No. 243,172.

To all whom it may concern:

Be it known that I, WILLIAM H. HILL, a citizen of the United States, residing at Manati, Porto Rico, have invented certain new and useful Improvements in Kerosene Vaporizers, of which the following is a clear, full, and exact description.

This invention relates to apparatus for volatilizing or vaporizing liquid fuels, and particularly to apparatus in which the liquid fuel is transformed into its gaseous or vaporized state without first being atomized.

An object of the invention is to provide a liquid fuel volatilizing apparatus in which the heavier liquid fuels, such as kerosene, may be completely or substantially completely volatilized without injury to the combustible properties of any of the constituents of the fuel.

Another object of the invention is to provide apparatus for volatilizing liquid fuels, in which the volatilizing means acts directly upon the fuel, that will operate to vaporize only enough fuel to meet the demands upon the apparatus, as, for example, when operating in conjunction with an internal combustion motor.

The invention aims also to provide means for volatilizing a liquid fuel, in which each of the constituents of the fuel will be acted upon directly by the volatilizing means and yet will be volatilized at a temperature which will secure complete or substantially complete volatilization without excessive heat.

An important feature of the invention is the arrangement, in combination with a differentially heated surface for effecting the volatilization of the constituents of the fuel at heats appropriate to the respective constituents, of means for directing the fuel to be volatilized over said surface in a film and in such manner that selective volatilization is effected by appropriately heated parts of the surface.

Another important feature of the invention is the provision of means for at once conducting away from the volatilizing means the different constituents of the fuel as they are volatilized, and of means where-

by the action of the apparatus is proportioned to the demand made upon it.

Other objects and important features of the invention will appear from the following description and claims when considered in connection with the accompanying drawings, in which—

Fig. 1 is a vertical section through liquid fuel volatilizing means embodying the present invention;

Fig. 2 is an end view of the apparatus shown in Fig. 1, looking from the right;

Fig. 3 is a plan view partly in section;

Fig. 4 is a perspective detail of the means for preventing slopping over of the fuel; and

Fig. 5 is a view in elevation and partly sectional showing the volatilizing means, the associated gas and air mixer, and the electric primer for use in starting an internal combustion motor.

As hereinabove suggested, the liquid fuel volatilizing means of the present invention is intended to operate directly upon the fuel without the intervention of means for atomizing the fuel or mixing it with air. To this end the illustrated device comprises a cylindrical chamber 2, bounded by a wall 4, which constitutes the volatilizing means proper, this wall being arranged to be differentially heated so that different parts of the wall are heated to different temperatures. The chamber also has a bottom 6 provided with an internally and externally threaded extension or hollow boss 8.

The means for heating the wall 4 of the chamber 2 in the illustrated construction comprises a casing 10 having open ends 12 and 14, constituting, respectively, intake and exit openings for the motor exhaust gases or other suitable heating fluid. The casing 10 is shaped between its ends 12 and 14 to receive the lower flanged part of the volatilizing means, this part of the wall 4 of the volatilizing means being provided with relatively wide heat-collecting flanges 16, the upper one of which, shown at 18, is provided with a shoulder 20 bearing against the upper face of the casing 10. A

nut 22, threaded upon the boss 8 of the bottom 6 of the volatilizing means and bearing against the bottom of the casing 10, clamps the shoulder 20 against the upper face of 5 said casing 10 and thus rigidly unites the casing 10 with the volatilizing chamber. Above the flange 18 and outside the casing 10, the wall 4 of the volatilizing chamber 2 is provided with heat radiating flanges 10 24, which are preferably somewhat narrower than the heat-collecting flanges 16.

The heat collected by the flanges 16, and directly collected by the wall 4 within the casing 10, is conducted to some extent up 15 through the wall 4 and outside said casing. A part of this heat will be radiated by the lower flanges 24, thus reducing the temperature of the wall just outside the casing 10 below that inside said casing, and the further radiating action of the flanges 24 above 20 the lower flanges 24 will cause a still further reduction of the amount of heat conducted up the wall, thus producing a decided differential in the temperature of the wall 4 at different points, the upper end of the wall 25 being the least heated.

The object of thus differentially heating the wall 4 is to provide for volatilizing the different constituents of the liquid fuel, for 30 example kerosene, at their appropriate heats of volatilization without over-heating, and the purpose of the particular relative arrangement of the differently heated parts of the surface in the illustrated device is to 35 provide for passing the fuel to be volatilized first over the least heated parts of the surface, in order first to volatilize the more volatile constituents of the fuel before the less volatile parts are directed over the more 40 heated parts of the surface. In the illustrated construction, the fuel to be volatilized is introduced into the upper end of the chamber 2 and is caused to flow down over the surface of the wall 4 in a relatively 45 thin film, means being provided for directing the fuel to be volatilized substantially over the whole inner surface of the wall 4.

The illustrated means for introducing the liquid fuel to be volatilized into the volatilizing means, and for directing it over the heat imparting surface of the wall 4, comprises a chambered part 26 threaded upon the upper part of the wall 4, the wall 4 having an exteriorly beveled or frusto-conical 55 part 30 projecting into the chamber 28 within the member 26, the inner wall of the chamber 28 about the beveled upper end 30 of the wall 4 being cylindrical. An annular groove 35 is thus provided about the 60 upper end of the wall 4, which communicates with a chamber 32 in a lateral extension 34 of the member 26, this groove being adapted to carry the liquid fuel about the upper end of the wall 4, and to constitute

a spill-way from which the liquid fuel will 65 be fed to the inner surface of the wall 4 to meet the demands upon the volatilizing means. To prevent slopping of the fuel over the upper edge of the wall 4, in the event 70 that the device is carried upon a moving vehicle, a guard 36 is provided, this guard having a sleeve portion fitting within the upper end of the chamber 2 and having perforations 38, preferably spaced evenly along the upper edge of the wall 4, through 75 which the liquid fuel may flow over into the chamber 2. The overhanging part 40 of the guard 36 projecting over the groove or spill-way 35 prevents slopping over the edge of an excess amount of the liquid fuel in the 80 case of sudden tilting of the device.

The liquid fuel to be volatilized is preferably fed to the chamber 32 and to the groove or spill-way 35 by gravity from a suitable tank sufficiently elevated to give the 85 required pressure, this tank (not shown) being connected by a pipe 42 and union 44 to a nipple 46 threaded into a boss 48 in the bottom of the chamber 32.

The nipple 46 at its upper end is provided 90 with a valve seat 50 for a valve 52, carried by a valve stem 54 connected to one arm of a lever 56 fulcrumed in the walls of the chamber 32, the other arm of this lever 56 being adjustably connected to a rod 58 carrying at its lower end a float 60. A spring 62, surrounding the stem 54 and bearing against an adjusting plug 64 in which the stem 54 is guided, is so adjusted that the float 60 and valve 52 are counter-balanced, 95 substantially in the position shown in Fig. 1, with the valve slightly opened and the float slightly above the bottom of the chamber 2.

In this position of the parts, fuel will be 100 constantly fed to the chamber 32 and will overflow the upper edge of the wall 4 and run down over the heated inner surface of wall 4 until it is completely volatilized and until the pressure of the gas within the chamber 2 is sufficient to overcome the pressure upon the fuel, due to the elevation of the fuel containing tank. The pressure of the gas in the chamber 2 will of course vary 105 with the demands made upon the volatilizing means, and the rate of flow of the liquid fuel to the volatilizing means will therefore be varied proportionately.

The volatilized or vaporized fuel is conducted away from the chamber 2 through a pipe 66, connected by a union 68 to a threaded boss 70 upon a removable cover 72, at the upper end of the chamber 28, the pipe 66 and the opening 74 through the cover 72 and boss 70 being of relatively small diameter to insure high speed of travel of the volatilized fuel or gas, thus preventing condensation. If the volatilized or vapor-

ized fuel is to be utilized for the operation of an internal combustion motor, it must be mixed with air or oxygen to form an explosive mixture, and in such case the pipe 5 66 is preferably connected to an air mixer intermediate between the volatilizing means and the manifold of the motor, a suitable mixer for this purpose being shown in Fig. 5 of the drawings.

10 The illustrated mixer comprises a hollow casting 76 having a flange 78 surrounding an opening at one end for connection with the manifold of the motor to be supplied, and having an air intake opening 80 15 surrounded by a valve seat for a valve 82 controlling the amount of air taken in to be mixed with the vaporized fuel. The vaporized fuel is conducted into the chamber 84 of the mixer through a pipe 86 of substantially the same diameter as the pipe 66, this pipe having at its upper end a valve seat for a needle valve 88 pivotally connected to a lever 90 fulcrumed at one end upon a link 92 pivoted upon an ear or ears 20 94 integral with the casting or casing 76 and pivotally connected at its other end to the stem 96 of the valve 82. The stem of the needle valve 88 is threaded for adjustment with respect to the lever 90 and also to 25 receive a nut 98, against which bears a spring 100 connected at one end to the casting 76. By adjusting the needle valve 88 with respect to the lever 90, the relative proportions of air and vaporized fuel taken 30 into the chamber 84 may be varied, and by adjusting the nut 98 the spring pressure upon the valves may be varied.

35 When the apparatus is used for supplying volatilized or vaporized liquid fuel for use in an internal combustion motor, the motor may be started by a more easily volatilized fuel, such as gasoline, or, as shown in the drawings, means may be provided for quickly volatilizing a sufficient amount of 40 the liquid fuel employed to start the motor and provide exhaust heat for the operation of the volatilizing means of the present invention. In Fig. 5 of the drawings is shown somewhat diagrammatically an electric 45 primer of the general type now in commercial use, comprising a heating coil 102 arranged to be completely immersed in the fuel in a chamber 104 connected with a fuel supply 106. By means of a three-way valve 50 108, the connection between the pipe 66 and the pipe 86 may be closed, and that between the pipe 107 leading to the chamber 104 may be opened, whereupon by sending an electric current through the coil 102, a supply of 55 heated fuel, sufficient to start the motor and provide exhaust heat, may be quickly obtained.

When the demand upon the volatilizing

apparatus is relatively low, as, for example, when the engine is idling, it is preferable 65 that the heat imparted to the volatilizing means shall be locally intensified, and to this end means is preferably provided for automatically locally varying the intensity of the heat imparted to the wall 4, in accordance with the variation in the demand 70 made upon the volatilizing means. The illustrated means comprises a valve or vane 112 carried upon a rock-shaft 114 in the casing 10 and arranged to swing across the inlet opening 12 and across the path of flow of the exhaust gases through the casing 10. Outside the casing, the shaft 114 is provided with an arm 116, to which is connected a spring 118 attached at its other end to the 75 casing 10, the spring 118 tending to move the valve or vane 112 in the direction to close the opening 12.

80 From an inspection of Fig. 1 of the drawings, it will be seen that the valve or vane 112 will be swung more or less toward a horizontal position, in accordance with the pressure or speed of flow of the exhaust through the casing 10, and that the exhaust will therefore be directed over a greater or less number of the heat gathering flanges 16, in accordance with the pressure exerted upon the vane 112. In order further to insure such direction of the exhaust, extensions 120 of the flanges 16 are preferably 85 cast integral with the casing 10 and so shaped that they substantially meet the path of swing of the lower end of the vane 112, thus shutting off the upper flanges 16 90 from the exhaust gases.

95 If, for any reason in the operation of the device, the liquid fuel should be fed to the inner surface of the wall 4 more rapidly than it can be converted into its vaporized or gaseous state, this fuel flowing down into the bottom of the chamber 2 will raise the float 60 and close the valve 52, thus shutting off a further supply until that within the chamber 2, and particularly that which has fallen to the bottom of the chamber 2, has 100 been volatilized. The float 60 will also operate to stop the further supply of fuel to the volatilizing means in the event that impurities in the liquid fuel, such as the heavier lubricating oils, have accumulated in the bottom of the chamber 2. Such impurities may be drawn off through the hollow boss 8, which is preferably normally closed by a plug 122.

105 110 What I claim as new is:—

115 120 125 1. In apparatus of the class described, means for volatilizing a liquid fuel, comprising a heated surface, means for directing the fuel in a film over said surface, a chamber for receiving the volatilized fuel, a fuel supply and means whereby the opera-

tion of the fuel supply is governed by the amount of unvolatilized fuel in said chamber.

2. In apparatus of the class described, means for volatilizing a liquid fuel, comprising a heated surface, means for directing the fuel in a film over said surface, a

chamber for receiving the volatilized fuel, a fuel supply governed by the pressure of the volatilized fuel and means whereby the supply of fuel is also governed by the amount of unvolatilized fuel in said chamber. 10

WILLIAM H. HILL.
